UNITED STATES PATENT OFFICE.

JESSE D. COTTRELL, OF PROVIDENCE, RHODE ISLAND.

AUTOMATIC SWITCH MECHANISM FOR STREET-RAILWAYS.

SPECIFICATION forming part of Letters Patent No. 710,432, dated October 7, 1902.

Application filed May 13, 1902. Serial No. 107,204. (No model.)

To all whom it may concern:

Be it known that I, JESSE D. COTTRELL, of Providence, in the State of Rhode Island, have made certain new and useful Improvements 5 in Automatic Switch Mechanisms for Street-Railways; and I do hereby declare that the following specification, taken in connection with the drawings making a part of the same, is a full, clear, and exact description thereof.

10 Figure 1 is a plan of my invention, showing end of car and double switch. Fig. 2 is another plan showing single switch. Fig. 3 is a view of the automatic operating device attached to the car. Fig. 4 is a vertical section 15 of same. Fig. 5 is a bottom view of the segmental lever. Fig. 6 shows the lever for setting the switching device. Fig. 7 is a side view of car-platform, showing the devices for the vertical operation of the segmental lever.

20 The object of my invention is to produce reliable and convenient mechanism for automatically switching railway-cars which shall at all times be under the easy adjustment and control of the motorman; and it consists in 25 the devices and the arrangement thereof, as hereinafter described.

In the drawings, A, Fig. 1, is a car running upon rails B C.

30 D is an iron plate set in the ground, to which is pivoted a forked lever E, the small end of which is pivoted to a bar F, which connects the switch-rails G H.

I is a vertical cylinder attached to the car and containing the automatic devices for operating the switch through the forked lever E.

35 J is an upright shaft projecting beyond the cylinder at either end. To the top of the shaft J is attached a lever K and at the bottom a segmental lever L, having a roller P P at each 40 extremity. Around the shaft J is a spiral spring M, which is confined between the bottom of the cylinder I and a collar N, fixed to said shaft. Over the lever K is a fixed guide O, having a doubly-inclined under surface 45 terminating in slots Q Q.

The operation of my invention is as follows: As the car approaches the switch the motorman turns the lever K to the right or left, depending upon the direction which he wishes 50 his car to take. As the lever K is turned it is forced downward by means of the inclined surface of the guide O, along which it must

pass, overcoming the resistance of the spring M until it reaches the slot at the end. As the car continues its forward movement the lever 55 L comes in contact with the point of one tine of the forked lever E, and the roller of the lever L travels along the side of the tine, which increases in width in the direction of the pivotal point, carrying the lever to one side and 60 bringing about the adjustment of the switch, as will be readily understood. When the adjustment of the switch is completed, one of the rollers P on the end of the lever L will have reached its slot R in the lever E, and 65 the continued movement of the car will create a pressure against the shoulder S of the slot R sufficient to give the lever L a rotary movement, which rotary movement of the lever L communicates a rotary movement to 70 the shaft J, which releases the lever K from the slot Q, when the lever K, through the action of the spring M, will be carried back to its original position, and also the shaft J. The shaft J being thus carried upward ele- 75 vates the lever L and carries it out of the reach of other objects as the car proceeds on its way until such time as the motorman may make another adjustment for another switch. It will thus be readily seen that the only hand 80 manipulation required will be the preliminary adjustment of the lever K by the motorman as the car approaches the switch, the further operation of the mechanism being wholly automatic. Whenever a single switch 85 is sufficient for the purposes desired, one tine of the forked lever E may be omitted, as shown in Fig. 2, the form of the tine retained being, however, the same as shown in Fig. 1.

The cylinder I may be attached to the truck 90 of the car, as shown in Fig. 7, and extend upward through the car-platform without being attached to the latter, which will have the effect of preventing the communication of any vertical or rocking movement of the car 95 to the segmental lever L.

What I claim as my invention, and desire to secure by Letters Patent, is—

1. In a device of the class described, the combination with a car, of a tubular sleeve 100 vertically mounted thereon, a rod mounted in said sleeve, switch-contacting means carried by said rod, a lever for turning said rod, and means carried by the lower end of the rod for

- throwing the switch, substantially as set forth.
2. In a device of the class described, the combination with a car, of a circular tubular chamber mounted thereon, a rod within said chamber, a lever for rotating said rod, a guide for the switch, and spring-actuated means for returning the switch to its normal and operative position after the railway-switch has been actuated by the contacting means carried on the rod, substantially as set forth. 25
3. In a device of the class described, the combination with a car, of a sleeve mounted thereon, a vertical shaft operating within said sleeve and receiving a rotary movement through a lever attached to the top thereof, and a segmental lever provided with rollers at its lower end adapted to engage and operate a railway-switch, substantially as set forth. 30
4. In a device of the class described, the combination with a car, of a vertical sleeve carried thereby, a rod rotatably mounted in 35
5. In a device of the class described, the combination with a street-railway car, of a vertical sleeve carried thereby, a rod rotatably mounted on said sleeve, a lever for actuating said rod, an incline guide for the lever, said guide being provided with a cut-away portion for retaining the lever and holding the rod in contact with the street-railway switch, and a device carried by the said rod for causing the lever to return to its normal inoperative position after contact with the 40 railway-switch, substantially as set forth. 45

JESSE D. COTTRELL.
